JOSEPH P. FEENEY, OF KEARNY, NEW JERSEY, ASSIGNOR TO CONGOLEUM-NAIRN INC.,
OF KEARNY, NEW JERSEY, A CORPORATION OF NEW YORK

EJECTOR MECHANISM FOR AUTOMATIC INLAYING APPARATUS

Application filed January 30, 1931. Serial No. 512,267.

The present invention relates to automatic equipment for cutting and inlaying linoleum or the like, and more particularly to the selector and ejector mechanism employed in such equipment.

One major object of the invention is to provide a novel ejector assembly adopted to produce an almost unlimited number of inlaid patterns or widely varying configurations.

10 Another major object is the provision of a universal type of selector and ejector mechanism of improved construction. A still further object is the provision of a selector and ejector mechanism adapted to cut and deposit 15 inlays of very small dimensions.

Referring to the drawings:

Figure I is a partial section through a linoleum cutting and inlaying cylinder illustrating the method of assembling and operating ejector mechanisms of the present invention.

Figure II is a partial plan view of a linoleum cutting and inlaying cylinder, showing one form of assembly of the ejectors of the 25 present invention;

Figure III is a plan view of a complete ejector;

Figure IV is a plan view of the ejector block;

30 Figure V is a full elevation of the ejector in the direction of the arrow A, Figure III;

Figure VI is a full elevation of the ejector in the direction of the arrow B, Figure III;

35 Figure VII is a sectional elevation of the ejector on the line C—C, of Figure III;

Figure VIII is a sectional elevation of the ejector on the line D—D, of Figure III.

The ejector mechanism of the present invention is basically novel, in that it provides, for the first time, a universal type of multiple unit ejector composed of a plurality of independent sub-ejectors adapted to function either singly or collectively. The mechanism 40 consists essentially of an ejector block, a major sub-ejector and one or more minor sub-ejectors mounted in operative relation. Each sub-ejector is adapted to function independently to eject and deposit an inlay of a different configuration, or the three components

of a single complete ejector may function collectively to eject and deposit a unit inlay. Also various combinations of sub-ejector components of a plurality of ejectors may function collectively to eject and deposit unit inlays. The following is a description of a preferred embodiment of the invention, reference being made to the accompanying drawings.

55 *The ejector block*

The ejector block 20, Figures IV and V, is usually formed of brass and is provided with an offset and projecting portion 21, adapted to be press-fitted into a cooperating recess in the cutting and inlaying cylinder 10. The block is drilled to provide a plurality of spindle openings 22, 23, and 24, the opening 22 being concentric with the axis of the projection 21 and the latter two being positioned relatively thereto as illustrated. Spindle guideways 26 are cut adjacent each opening and the openings 23 and 24 are also counter-bored to provide spindle retaining shoulders 25. The block is slotted at 27 and 28 to provide recesses for the reception of cutting knives, and also at 29, 30, 31, and 32 to provide flexible sections 33 and 34 adjacent the spindle openings 23 and 24 respectively, for the purpose hereinafter described.

60 *The major sub-ejector*

The major sub-ejector, Figure VIII, is preferably constructed in the manner described and claimed in United States Letters Patent 1,784,487, granted December 9, 1930. An internal shoulder is formed within the spindle opening 22 by means of a bushing 36 threaded into the tapped outer end of the opening. The bushing is also centrally bored to provide an opening in which the ejector spindle 12 slides. The spindle is provided with a collar 37, working within the inner end of the opening 22. Between the bushing 36 and the collar 37 is confined a light coil spring 38 which serves to retract the spindle after it has been pushed outwardly by the pattern or inlaying rolls. To guide the spindle in its reciprocating movement and to prevent its rotation, projecting lugs 39 are formed on

the collar 37 and are adapted to slide in the longitudinally extending guideways 26. The spindle 12 is threaded at its outer end 40 and is provided with a shoulder 41. The 5 ejector plate 42 is perforated and engages the stem of the spindle, abutting the shoulder 41. The plate 42 is counter-bored to receive a round slotted nut 43 which threads onto the stem 40 of the spindle. Interposed between 10 the plate 42 and the nut 43 is a cup washer 44 which is adapted to be swaged into the slots 45 of the nut 43 and the slots 46 of the plate 42, after the nut has been tightened onto the spindle, thus positively interlocking the plate 15 and spindle.

The minor sub-ejectors

The minor sub-ejectors are substantially identical with each other in construction although the ejector plates are of different configuration. Each sub-ejector comprises a spindle 47 and an ejector plate 48 (or 48') swaged onto one end of the spindle. Each spindle, intermediate its length, is provided 25 with an enlarged collar portion 49 adapted to slide within the counter-bore of opening 23 or 24 but to engage the shoulder 25 of the block 20. Each spindle is also provided with strengthening ribs 50 sliding within 30 the guideways 26 and serving also to prevent rotation of the spindle during its reciprocating movement. The minor sub-ejectors are positioned within the respective openings 23 and 24 in the block 20 by forcing the collar 35 portion 49 past the shoulder 25, the flexible sections 33 and 34 yielding to permit such passage. Thereafter the sections 33 and 34 return to normal position and prevent the escape of the spindles so that, in operation, 40 each spindle is limited in its outward movement by the engagement of the enlarged collar portion 49 with the shoulder 25. When, however, it is desired to dis-assemble the ejector, each spindle 47 may be withdrawn by 45 springing the flexible walls 33 (or 34) and forcing the collar portion 49 past the shoulder 25. Tapped holes 51 are provided to facilitate this operation.

The ejector assembly

The several sub-ejectors, when assembled with the block 20 in the manner described, form a complete multiple unit ejector mechanism of universal type. It will be observed 55 that the ejector plates 42, 48 and 48' are each of different configuration, but when assembled, form a complete unit which is of square configuration. It will also be noted that the minor sub-ejectors are interchangeable and, 60 when interchanged, form an ejector mechanism complementary in arrangement to the one particularly described. Where the design requires an inlay of a configuration conforming to that of the several plates of the 65 major sub-ejector and one or both minor sub-

ejectors, a single plate of such configuration may be mounted on the spindle 12 of the major sub-ejector and the plates 48 or 48' or both, as the case may be, may be dispensed with.

Automatic equipment for the manufacture of inlaid linoleum or the like, usually comprises a number of cutting and inlaying cylinders 10, each cylinder having assembled on its periphery a plurality of the ejector mechanisms. One form of assembly of the inlaying ejectors 11 of the present invention is shown in Figures 1 and 2. Cutting knives 52 are interposed between the adjacent ejector mechanism and also in the slots 27 and 28 of the ejector block 20 between the plates 42, 48 and 48' of each ejector. It will of course be understood that where the inlays to be cut and deposited are of a configuration embracing a plurality of contiguous ejector plates, the cutting knives between such plates will be removed so that the inlays may be cut and deposited in unit pieces. Within the cylinder is positioned a pattern roll 13, the surface of which is provided with a plurality of recesses 14 conforming to the desired inlaid pattern. As the cylinder 10 rotates, certain of the ejector spindles enter the recesses 14 thus permitting the corresponding pattern tesserae 17 to be retained. The ejector spindles not entering recesses on the pattern roll are forced outwardly by the latter and eject the material between the retained tesserae, the ejected material being swept away by the brush 15. As the cylinder 10 continues its rotation the ejector spindles 12 are operated upon by the smooth surface inlaying roll 16, also positioned within the cylinder, and the initially retained tesserae 17 are ejected and deposited upon a suitable backing 18 in pattern relation. It will be apparent that by employing different pattern rolls 13 in which the location of the recesses 14 is varied, the universal multiple-unit ejector assembly is adapted to produce an almost unlimited number of distinct patterns.

Another most important feature of the present invention is that the ejector mechanism constructed in accordance with its teachings, is capable of cutting and depositing inlays of very small dimensions. Thus, the major sub-ejector is adapted to deposit an inlay having a minimum dimension of approximately one-half inch while the minor sub-ejectors are adapted to deposit inlays having a minimum width of about one-eighth inch and a length corresponding to the minimum dimension of the major sub-ejector. The capacity to accomplish these results remarkably increases the scope of patterns which may be manufactured with automatic equipment provided with such ejector mechanism.

In addition to the above enumerated ad-

vantages, the ejector mechanism of the present invention is both simple and rugged in construction, and positive and safe in operation. Repairs, when necessary, are greatly facilitated by the manner in which the elements of the mechanism are assembled. Any sub-ejector of a single mechanism may be removed and replaced without disturbing any other element of the mechanism. Similarly, any ejector mechanism may be removed and replaced as a unit without affecting adjacent mechanisms.

It will be apparent to those skilled in the art that this invention contributes an important advance in the manufacture of inlaid linoleum in that it provides, for the first time, a universal type of multiple unit ejector mechanism for cutting and depositing inlays. In the teaching of the construction of a mechanism of this character, the present inventor asserts his pioneership.

Claims:

1. A universal ejector mechanism for cutting and depositing inlays comprising an ejector block, a plurality of spindle openings in said block, an ejector operatively mounted in each of said spindle openings, at least one of said spindle openings being formed by a wall comprising a flexible section.
2. An ejector mechanism for cutting and depositing inlays comprising an ejector block, a spindle opening in said block, the wall about said spindle opening comprising a flexible section, a shoulder formed within said opening, an ejector spindle, and an ejector plate carried thereby, said ejector spindle having an enlarged cross section intermediate its length and being adapted to freely reciprocate within the spindle opening but having its movement normally limited by the shoulder formed within said opening.
3. An ejector mechanism for cutting and depositing inlays comprising an ejector block, a spindle opening in said block, the wall about said spindle opening comprising a flexible section, a shoulder formed within said opening, an ejector spindle having strengthening ribs integral therewith, and an ejector plate carried thereby, said ejector spindle having an enlarged cross section intermediate its length and being adapted to freely reciprocate within the spindle opening but having its movement normally limited by the shoulder formed within said opening.
4. An ejector mechanism for cutting and depositing inlays comprising an ejector block, a spindle opening in said block, the wall about said spindle opening comprising a flexible section, and an ejector operatively mounted to freely reciprocate within said spindle opening.

In testimony whereof, I affix my signature.
JOSEPH P. FEENEY.
